ATTACHMENT FOR CONVERTING SEMI-AUTOMATIC FIREARMS TO FULL AUTOMATIC

Stanley J. Ketterer, St. Louis, Mo.

Application October 8, 1948, Serial No. 53,578

1 Claim. (Cl. 89—140)

(Granted under the act of March 3, 1883, as amended April 30, 1928; 370 O. G. 757)

1

The invention described herein may be manufactured and used by or for the Government for governmental purposes without the payment of any royalty thereon.

This invention relates to an attachment for a rifle of the semi-automatic type whereby such firearm can be converted to fire fully automatic.

Some firearms are designed to fire semi-automatically, particularly military firearms, as with such firearms it is highly desirable that the loading operation be accomplished mechanically thereby greatly increasing the rapidity of fire with a minimum of effort on the part of the shooter. In some instances however, particularly in time of war, a much higher volume of fire may be required and if a rifle is equipped to fire only semi-automatically, such volume of fire can not be delivered.

While many attempts have been made to convert a semi-automatic firearm to fire fully automatic, such conversions as have been evolved are highly complicated mechanisms requiring fabrication to a precision of a very high order. Further these complicated mechanisms generally required considerable modification of the firearm itself thereby adding to the cost of converting the firearm to full automatic fire.

Accordingly it is an object of this invention to provide an attachment for semi-automatic firearms to convert such firearm to fire fully automatic wherein the attachment is simply and easily fabricated and can be assembled to the firearm with no alteration of the firearm other than minor cuts to the stock thereof.

A particular object of this invention is to provide an attachment for the U. S. rifle, cal. .30 M1 whereby such rifle may be quickly converted to fire fully automatic.

This invention consists essentially of a lever-like member pivotally mounted to the firearm and having a cam member on one end engageable by the operating rod of the firearm. A depending arm is provided on the pivoted end of the lever which is engageable with the primary sear of the firearm to effect release of such primary sear from engagement with the hammer when the operating rod of the firearm strikes the cam associated with the lever.

The invention to be presently described in detail is preferably applied to a rifle of the type known as the U. S. rifle, cal. .30 M1 and such application is chosen to best illustrate the manner of use of this invention. Such a specific illustration should not be construed as limiting the invention solely to use with such firearm as this

2

invention may be applied to substantially all firearms equipped for semi-automatic fire; however the preferred embodiment is shown in the accompanying drawings in which:

5 Fig. 1 is a fragmentary longitudinal view partly in section of a firearm showing the attachment mounted thereon.

Fig. 2 is a plan view showing the method used to mount the attachment to the stock.

10 Fig. 3 is an enlarged view showing the locking device elements.

Fig. 4 is an enlarged front view showing the positions of the cam for automatic and semi-automatic firing.

15 In Fig. 1 there is shown a rifle having a semi-automatic trigger mechanism such as is embodied in the U. S. rifle, cal. .30 M1. Such rifle comprises mainly a receiver 10, a bolt 11 slidably mounted for reciprocating movement in receiver

20 10, an operating rod 12 connected to bolt 11 and slidably mounted on receiver 10. A stock 13 and a trigger guard 14 complete the main elements of the firearm. Trigger guard 14 includes a pivoted hammer 15 secured to such trigger guard by a pin 16.

25 A trigger 17 is pivotally mounted on trigger guard 14 and a primary sear 18 is pivotally mounted on trigger 17. Primary sear 18 is engageable with rearwardly projecting sear engaging lugs 19 provided on hammer 15. Hammer engaging lugs 20 are provided on the upper end of trigger 17 which are engageable with forwardly projecting lugs 21 on hammer 15.

30 A spring biased plunger 22 contained within a housing 23 and mounted on trigger guard 14 is provided to bias hammer 15 forwardly from a cocked position to a fired position. The above elements are all elements of the well known U. S. rifle, cal. .30 M1 and have been briefly described to better show the cooperation of such elements with the members of this invention.

35 The device of this invention comprises a lever-like member 24 pivotally mounted to stock 13 by a transverse pin 25. Such pin is located substantially in line with sear 18. Lever 24 is offset as shown at 26 in order to clear trigger guard

40 14 as shown in Fig. 2. Stock 13 is cut away slightly as shown in such figure to accept lever 24. An integral depending arm 27 on lever 24 just contacts primary sear 18 as shown in Fig.

45 50 1 when hammer 15 is held in the cocked position by sear 18.

55 A spring 28 preferably integrally formed on the underside of lever 24 near the forward end thereof projects downwardly and contacts the bottom of a recess 29 provided on the inside of

stock 13. Such spring is provided to bias lever 24 upwardly for a purpose as will later appear. A normally vertically disposed cam member 30 is hinged to the forward end of lever 24 by a pin 31. Cam 30 projects upwardly into the path of operating rod 12 so that such cam may be contacted by a handle 32 provided on operating rod 12 as will be later described. A locking device comprising a wedge-shaped detent 33 is provided to yieldingly secure cam 30 in either an upright or depressed position. Detent 33 is engageable with a lug 34 provided on the forward end of lever 24 in a suitably shaped notch 35 therein. A counterbored hole 36 in detent 33 is provided to receive hinge pin 31 and a spring 37 surrounding such pin. Pin 31 is provided with a head 38 against which one end of spring 37 abuts while the other end of such spring strikes bottom of counterbored hole 26. When cam 30 is assembled to lever 24, pin 31 is preferably secured to lug 34 by a screw 39. Thus the bias of spring 37 against detent 33 urges such detent into notch 35 of lug 34 thereby maintaining cam 30 in either of the two positions selected.

Those familiar with the U. S. rifle, cal. .30 M1 trigger mechanism appreciate that in the normal or unpulled position of the trigger and with the hammer in the cocked position, lugs 20 of trigger 17 are in engagement with lugs 21 of hammer 15 to hold such hammer in the cocked position. Upon release of trigger 17, lug 20 of trigger 17 slides off of hammer lugs 21 thereby releasing hammer 15. Upon discharge of the cartridge in the firearm, operating rod 12 is forced rearwardly carrying with it bolt 11 which rotates hammer 15 to the cocked position as shown in Fig. 1. In such figure the primary sear 18 engages hammer lugs 19 to hold such hammer in the cocked position. Primary sear 18 is provided to retain hammer 15 in the cocked position while the trigger is still in a pulled rearward position. If such sear was not provided hammer 15 would then follow bolt 11 forwardly to the battery position as there would be nothing restraining such movement of hammer 15. The reason therefore is due to the fact that the trigger can not be released rapidly enough after discharge of a cartridge whereby the trigger could return to a hammer engaging position before the bolt had reached the battery position.

In view of the above, full automatic fire is obtained by releasing primary sear 18 from engagement with hammer 15 shortly after bolt 11 has reached its locked battery position without taking the finger off of trigger 17. Bolt 11 however must be in a locked battery position otherwise an unsafe condition would result.

Accordingly by raising cam 30 to the position shown in Fig. 1, handle 32 of operating rod 12 will then strike the sloped top surface of such cam just after bolt 11 has reached the locked battery position, whereupon lever 24 is pivoted downwardly or in a clockwise direction as shown in Fig. 1 thereby moving arm 27 in a corresponding clockwise direction. Arm 27 being in engagement with primary sear 18 rotates such sear in a counter-clockwise hammer releasing position whereupon hammer 15 goes forwardly to discharge a cartridge in the chamber of a fire-

arm. On the recoil stroke of bolt 11 and operating rod 12, lever 24 is raised to its normal operating position by the bias of spring 28 thereby again positioning cam 30 to be engaged by handle 32 of operating rod 12 on the counter-recoil movement of operating rod 12 whereupon the release of hammer 15 is effected as just described. Such cycle of operation will continue as long as trigger 17 is pulled rearwardly or until the cartridges contained in the clip are exhausted.

The firearm is readily returned to its normal firing condition by simply folding down cam 30 as shown in Fig. 4 thereby permitting hammer 15 engaging lugs 20 of trigger 17 to function in a normal semi-automatic manner.

It is thus apparent to those skilled in the art that there is here provided a simple attachment readily adapted to any firearm of the semi-automatic type for converting such firearm from semi-automatic fire to full automatic fire or back to semi-automatic fire as may be desired. Such attachment is cheaply and easily fabricated and is positive in operation. It is also desired to emphasize that such attachment can be assembled to a firearm with a minimum of modification of the existing firearm.

I claim:

In an automatic firearm having a bolt operating element reciprocable between a battery position and a recoil position, in combination, a spring pressed hammer pivotally mounted in the firearm for movement between a cocked position and a fired position, a trigger pivotally mounted in the firearm, said trigger having a lug to yieldingly hold said hammer in the cocked position when said trigger is in an unpulled position, a sear pivotally mounted to said trigger and engageable with said hammer in the pulled position of said trigger, a lever member pivotally mounted on the firearm, said lever member having a depending arm for contacting said sear, cam means on said lever member normally projecting upwardly into the path of the bolt operating element for contact thereby during movement into battery position whereby said lever member is pivoted so that said depending arm thereon moves said sear to release said hammer from the cocked position thereof, spring means operating on said lever member to return said cam means into the path of travel of said bolt operating element upon recoil movement thereof, and means for pivotally mounting said cam means on said lever member for selective movement into and out of the path of travel of the bolt operating element.

STANLEY J. KETTERER.
